H. W. CHENEY

CONTACT DEVICE

Filed Sept. 27, 1920

UNITED STATES PATENT OFFICE.

HERBERT W. CHENEY, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CONTACT DEVICE.

Application filed September 27, 1920. Serial No. 413,087.

To all whom it may concern:

Be it known that HERBERT W. CHENEY, a citizen of the United States, residing at Milwaukee, in the county of Milwaukee and 5 State of Wisconsin, has invented a certain new and useful Improvement in Contact Devices, of which the following is a specification.

This invention relates to electrical contact mechanisms embodying a new form of contact and support therefor.

One of the objects of the invention is the provision of a contact which may be easily and quickly removed from its support. 15 Another object is the provision of means whereby, even though the fastening means for the contact is somewhat loose, the contact will not drop away from its support.

Still another object is the provision of 20 means whereby the strains produced by the engagement of co-operating contacts will be taken chiefly by means other than the means fastening a contact to its support. Another object is the provision of a contact 25 having the aforementioned characteristics, which may be reversed with respect to its support. Other objects will appear hereinafter as the description of the invention proceeds.

30 The novel features of the invention will appear from this specification and the accompanying drawing forming a part thereof and disclosing an embodiment of the invention, and all those novel features are intended to be pointed out in the claims.

35 In the drawing; Fig. 1 is a front elevation of a contact mechanism embodying the invention.

Fig. 2 is a side elevation of a detail, along 40 the line II—II of Fig. 1 looking in the direction of the arrows, certain of the parts being removed.

The contact mechanism here shown, includes a movable contact 1 and stationary 45 contacts 2, 3. There may be as many sets of these contacts as desired, only one set appearing in the present front elevation. There may also be only one movable and one stationary contact as far as certain features 50 of the invention are concerned. Certain features of the invention may, moreover, be applied in only the stationary or only the movable contacts, if so desired.

The novel contact mechanism will be un-

derstood by a description of the contact 2 55 and the supporting means therefor. The contact 2 is provided with an attaching portion 4 having lateral projections 5, 6. These projections may be provided at any point along the opposite faces of the portion 4 60 but, as here shown, result in an attaching portion generally of T shape. The projection 6 is adapted to co-operate with a slot 7 in the rectangular supporting member 8 comprising the legs 9, 10. The rectangular 65 supporting member is here shown as fastened to a carrying rod 11, and to this end, is provided with a depression 12 to accommodate the surface of the rod, whatever the cross-sectional shape of the rod may be. 70 The supporting member is fastened to said rod by means of a clamp 13, in combination with bolts 14, 15. The leg 10 is spaced slightly from the clamp. The bolt 15 passes through an opening in one leg of the clamp 75 13, through an opening in the leg 10, an open ended slot 16 (see Fig. 2) in the portion 4 of the contact, through an opening in a plate 17 and into the threaded nut 18.

As will be seen clearly by reference to 80 Fig. 2, (in which the plate 17 and nut 18 have been removed) the contact 2 has a slot 16 in its attaching portion, substantially parallel to the general plane of the T. The slot 16 and bolt 15 are preferably of such 85 relative proportions that the bolt will clear the walls of the slot. The opening in the plate 17 is preferably just large enough for the passage of the bolt 15.

The result of the above described construction is that pressure on the contact 2 will result in a minimum stress on the bolt 15 inasmuch as such stresses are taken by the supporting member 8 and its associated parts through the action of the projection 6 95 and the slot 7. Furthermore, less tension is required in setting up the bolt and nut and even if there is a slight looseness, which might occur as a result of operating conditions, the contact 2 will not drop away from its support, being held by the engagement of the projections 5, 6 with the plate 17 and slot 7 respectively. This action is assisted by the resilience of the clamp 13 which draws the nut 18 against the plate 17 and 100 so keeps the latter under the projection 5 and also holds the attaching portion 4 of the contact, with its projection 6, in engagement 105

with the complementary parts of the leg 10. The contact 2 may moreover, be readily removed without completely unscrewing the nut 18. By reason of the construction of the 5 contact it may also be readily reversed with respect to its support, in case that becomes desirable.

What has been stated above, of course applies equally well to the contacts 1, 3. 10 Where, as in the present instance another contact or set of contacts 3 is involved, the two sets of contacts are conveniently supported by and related through an insulating plate 19, this plate being clamped between 15 the upper leg of the clamp 13 and the leg 9 of the rectangular supporting member 8 by means of the bolt 14. The bolt 14 may be threaded into the leg 9 or made functionally integral therewith in any manner, 20 as desired. The clamp 13 and associated parts may be insulated from the rod 11 by means of an insulating sleeve 20. It will be noted that, by reason of the relation of plate 19 to both of the clamps, the contacts 25 are held in rigid relation to the rods, no turning being possible.

The movable contacts 1 may be provided with any suitable form of actuating mechanism, and as this forms no part of the 30 present invention it will not be herein described.

It should be understood that it is not desired that the invention claimed be limited to the exact details of construction shown 35 and described for obvious modifications will occur to a person skilled in the art.

It is claimed and desired to secure by Letters Patent:

1. A contact having a portion for attaching the same to a support, said portion having an opening transverse to the general plane of said portion, and projections on said portion extending in opposite directions.

45 2. A contact having a portion of T shape for attaching the same to a support, said portion having an opening substantially parallel to the general plane of the T.

3. A contact having a portion of T shape 50 for attaching the same to a support, said portion having an open-ended slot substantially parallel to the general plane of the T.

4. In combination, a contact support having a contact surface provided with a slot, 55 a contact having a portion co-operable with said contact surface and a projection co-operable with said slot, and means for fastening said contact to said support.

5. In combination, a contact supporting- 60 member, a contact member co-operable with another contact, means for fastening said contact member to said support-member, and means including a slot in one of said members and a co-operating projection on the other of said members for taking strains

arising when said contacts are pressed together.

6. In combination, a contact support-member, a contact member having an open-ended slot said contact being co-operable 70 with another contact, means having a portion passing through said slot for fastening said contact member to said support member, and means including a slot in one of said members and a co-operating projection 75 on the other of said members for preventing disengagement of said contact member and support even though said fastening means is loose to a predetermined degree.

7. In combination, a contact having a portion of T shape, said portion having an open-ended slot substantially parallel to the general plane of said T, a supporting member for said portion having a slot co-operating with one end of the cross bar of said T, an apertured plate co-operating with the other end of said cross bar, and a bolt passing through said member, said portion and said plate.

8. In combination, a contact support having a slot, a contact member having a projection co-operable with said slot, said contact member having an opening, and means passing through said opening and clearing 90 the walls thereof for fastening said contact member to said support.

9. In combination, a rod, a switch contact, and means for supporting said contact from said rod and holding it rigid with respect thereto including a resilient clamp and a bolt passing through said clamp and said contact, said contact and supporting means being provided with complementary surfaces 100 for preventing relative motion between the same transverse to said bolt.

10. In combination, a round rod, a switch contact, means for fastening said contact to said rod including a clamp having a round engaging surface, and relatively stationary means for positively preventing movement 110 of said clamp around said rod.

11. In combination, a rod, a rectangular support-member having a depression at the outer apex of the right angle adapted to co-operate with said rod, a clamp around said rod having legs adapted to co-operate with said rectangular support-member one of said legs being spaced from said support-member, means for fastening said latter leg support-member, and said contact together, and means for fastening the other leg to said support-member.

12. In combination, a rod, a rectangular support-member having a depression at the outer apex of the right angle adapted to co-operate with said rod, a clamp around said rod having legs adapted to co-operate with said rectangular support-member, means for fastening one of said legs, said support-member, and said contact together, and

means for fastening the other leg to said support-member.

13. In combination, a rod, a rectangular support-member having a depression at the outer apex of the right angle adapted to co-operate with said rod, a clamp around said rod having legs adapted to co-operate with said rectangular support-member, one of said legs being spaced from said support-member, a bolt for fastening said leg, said support-member, and said contact together, said contact and said support member having complementary surfaces for preventing relative movement between said contact and said support transverse to said bolt, and means for fastening the other leg to said support-member.

14. In combination, a contact support, a contact having two legs substantially at right angles, one leg having a face engaging said support and the other having a contact

face substantially at right angles to said engaging face, a bolt passing through said engaging-leg and into said support for holding said leg against said support, and means whereby when pressure is put on said contact face tending to turn said engaging-leg about its end as a fulcrum, substantially no strains will be put on said bolt. 25

15. In combination, a contact support, 30 having a shoulder and an adjacent slot, a contact having a part with a face engaging said support and having portions complementary to said slot and shoulder, and having a contact face substantially at right angles to said engaging face, and a bolt 35 passing through said engaging-part and into said support.

In testimony whereof, the signature of the inventor is affixed hereto.

HERBERT W. CHENEY.
